HARVEY C. HAYES, OF WASHINGTON, DISTRICT OF COLUMBIA

ACOUSTICAL WAVE FILTER

Application filed March 3, 1927. Serial No. 172,391.

(GRANTED UNDER THE ACT OF MARCH 3, 1883, AS AMENDED APRIL 30, 1928; 370 O. G. 757)

My invention relates broadly to acoustical wave filters in which standing wave systems within tubes are utilized and relates more particularly to the application of the same to radio receiving sets.

The object of my invention is to eliminate static or strays in a radio receiving system and to amplify the pure signal received from the transmission station free from all extraneous noises.

The energy of a standing wave system within a tube has been found to be wholly kinetic at the loops and wholly potential at the nodes. Little or no energy, therefore, is expended against the tube at the loops of the signal since at this point the pressure outwardly from within the tube is equal to atmospheric pressure.

Applying this principle to radio receivers I have developed an acoustical wave filter that transmits waves of predetermined length without appreciable loss whereas those waves having a wavelength at variance with the selected waves will expend their energy and reduce their volume prior to detection or further amplification.

My invention consists substantially in the construction, combination, and arrangement of parts associated therewith or as will be more fully hereinafter set forth as shown by the accompanying drawings and finally pointed out in the appended claims.

Reference is to be had to the accompanying drawing forming a part of this specification in which like reference characters indicate corresponding parts throughout the several views and in which—

Figure 1 represents a radio receiving circuit in which such a device may be used, and—

Figure 2, represents a preferred construction of one form of my invention.

Figure 3 is an end view in section of one modification showing the arrangement of a plurality of tubes of structure similar to that shown in Figure 2.

Referring to Figure 2, numeral 1 represents the input terminals of a sound generating device 2, to which the output terminals 1' of Figure 1 are connected. The sound

generating device, such as a telephone receiver, consists of a sound generating diaphragm 7 actuated by the electrical current output of the radio receiver thus generating a sound having a frequency equal to that of the driving current.

The output from the sound generator traverses the tube 3, that has a rigid inert wall and which for simplicity of illustration and description is terminated by a sound reproducer 4 similar to the one 2 at the input end of the tube and which has been briefly described. However, I do not wish to limit myself to the use of input and output devices of similar structure.

Sound waves generated by diaphragm 2 traversing tube 3 cause the diaphragm 5 of the terminal magnetophone 4 to vibrate thereby generating an alternating electromotive force at its terminals 6 of the same frequency as that of the generating sound waves. This electromotive force can be used directly or in amplified form to energize an ordinary telephone or loud speaker.

If the frequency of the current driving diaphragm 7 is made of proper value, a standing wave system as represented at 8 will be formed in the tube 3 between the two diaphragms 7 and 5. In practice the tube length is made such that the standing wave system will be formed for a sound pitched at a frequency approximately 1000 vibrations per second.

This value is chosen for the reason that the ear is highly sensitive to sounds of this frequency and because most radio operators prefer to receive signals of this pitch.

The tube is made up of a plurality of sections 9, each section of which is separated from each other by slots 10. The length of each section 9 of the tube 3 is such that these slots 10 are located at the loops of the standing wave system 8 in the tube 3.

The energy of such a standing wave system being wholly potential at the nodes and wholly kinetic at the loops it follows, therefore, that little or no energy will escape from the tube if it is punctured or slotted transversely at the loops since the pressure against the tube wall at those points is equal to the

atmospheric pressure upon the outside of the tube. It is evident that the distance between slots along the tube is equal to a half wavelength of the sound that is transmitted substantially without loss.

5 Sounds of any other wavelength will not pass the slots or perforations 10 without loss of energy through the slots to the outside because the energy of the waves at those points will not then be wholly kinetic.

10 In particular the sounds generated by the so-called static components of the current are largely of the nature of impulses of a wide range of wave lengths. Since only a very 15 small percentage of the impulses produced thereby will coincide with the standing wave system 8 practically all of the impulses will be lost through the slots 10 and only the pure signal will be left when the standing wave 20 system reaches the diaphragm 5 of the output magnetophone 4.

25 As a result, the magnetophone 4 responds less rigorously to the static impulses than to the pure tone signal since the pure tone traverses the tube in practically undiminished volume.

30 The effectiveness of the device is dependent to a large extent on the number of sections of the tube and also on its diameter. In practice 35 a tube one half an inch inside diameter and consisting of 10 sections has given good results.

40 A modification still more efficient is the utilization of a plurality of tubes of smaller 45 cross-section and connected in parallel as shown in Figure 3, wherein each of tubes (3') is identical in structure with the tube 3 in Figure 2. The principles employed in the 50 construction and operation of this device are identical with those described in the operations of the device as Figure 1.

55 It will be understood that the above description and accompanying drawings comprehend only the general and preferred embodiment of my invention and that minor detail changes in construction, and arrangement of parts may be made within the scope of the appended claims and without sacrificing any of the advantages of my invention.

60 The invention herein described may be manufactured and used by or for the Government of the United States for governmental purposes without the payment to me of any royalty thereon or therefor.

65 Having thus described my invention what I claim is—

1. An acoustic filter comprising means for 65 converting non-acoustic energy into acoustic energy said acoustic energy being in the form of a standing wave having a plurality of components, means resonant to a predetermined component of said standing wave, a plurality of energy dissipating means in fixed positional relation to said resonant means and so positioned as only to dissipate energy from

other than the predetermined component of said standing wave and means for reconverting the undissipated acoustic energy into non-acoustic energy.

2. An acoustic filter comprising means for 70 converting non-acoustic energy into acoustic energy, said acoustic energy being in the form of a standing wave having a plurality of components, means resonant to a predetermined component of said standing wave, a plurality 75 of energy dissipating means in fixed positional relation to said resonant means and located at points on said resonant means where the energy of said predetermined component is wholly in kinetic form and means for 80 reconverting the undissipated acoustic energy into non-acoustic energy.
